UNITED STATES PATENT OFFICE.

WALTER A. HALL AND CHARLES W. HALL, OF NEW YORK, N. Y., ASSIGNEES TO RAILWAY IMPROVEMENT COMPANY, OF NEW YORK, N. Y., A CORPORATION OF NEW YORK.

CENTRIFUGALLY-CONTROLLED COASTING-INDICATING DEVICE FOR CARS OR TRAINS.

1,165,592.

Specification of Letters Patent. Patented Dec. 28, 1915.

Application filed March 20, 1911. Serial No. 615,535.

To all whom it may concern:

Be it known that we, WALTER A. HALL and CHARLES W. HALL, citizens of the United States, residing in the city, county, and State of New York, have made a certain new and useful Invention in Centrifugally-Controlled Coasting-Indicating Devices for Cars or Trains, of which the following is a specification.

10 This invention relates to devices and apparatus for use in indicating the time consumed by a car or train while coasting or drifting, that is, the time consumed during the travel of the car or train after current 15 has been cut off from the car or train propelling motor or motors and specifically to one form of such apparatus as shown in my co-pending application Serial No. 615,534, filed March 20, 1911.

20 The object of the invention is to provide a centrifugally operated control mechanism for controlling the coasting or drifting period indicating devices, which is simple in construction and efficient in operation.

25 A further object of the invention is to provide means for controlling the coasting or drifting period indicating mechanism by centrifugal action developed by the travel of the car or train while coasting or drifting.

30 Other objects of the invention will appear more fully hereinafter.

The invention consists substantially in the construction, combination, location and relative arrangement of parts, all as will be 35 more fully hereinafter set forth, as shown in the accompanying drawing, and finally pointed out in the appended claims.

In the accompanying drawing,—Figure 1 is a diagrammatic view showing a centrifugally controlled coasting indicating device embodying the principles of our invention. Fig. 2 is a broken detail view in plan of the centrifugally operated controlling devices. Fig. 3 is a similar view showing a slightly 45 modified arrangement of centrifugally operated controlling device embodying the principles of our invention. Fig. 4 is a view showing a portion of indicating mechanism adapted for use in connection with our 50 invention.

The same part is designated by the same reference sign wherever it occurs throughout the several views.

In the practical operation of street or other cars, railway trains, or the like, the 55 operating power is cut off from the car or train propelling motor before such car or train reaches the point where it is to stop, and thereafter while the operating or propelling motor is cut off the car or train 60 coasts or drifts without any other propelling power than its momentum. The time consumed during this coasting or drifting travel of the car or train after its propelling power has been cut off represents a saving of current or other power employed to operate the 65 train or car. Indicating devices or mechanism for indicating the time consumed by a car or train during the coasting or drifting travel thereof have been devised. In the 70 operation of such devices or mechanism it is important to provide means for setting the indicating mechanism in operation, only when the propelling power medium is shut off, and for arresting the recording mechanism when the car or train completes its 75 coasting or drifting travel.

It is among the purposes of our present invention to provide centrifugally operated control devices for arresting the operation 80 of the coasting or drifting period indicating mechanism, said centrifugally operated devices being actuated by the travel or movement of the car or train.

In carrying out our invention, we propose 85 to employ means for controlling the operation of the indicating mechanism, which means are controlled so as to be set in operation coincidently with the shutting off of the car or train propelling power, and which 90 are arrested when the propelling power is turned on, when the car or train brake mechanism is applied, and also when the coasting or drifting travel of the car or train has been completed. In respect to this last 95 mentioned feature of our invention we propose to employ centrifugally operated devices which are actuated by the travel of the car or train, in such manner that as the momentum of the car or train after its pro- 100

propelling power has been shut off decreases to the point where the travel or movement of the car is insufficient to operate the centrifugal devices, the indicating mechanism 5 is arrested automatically. This generally is the main purpose and object of our present invention. This object and purpose may be accomplished in many specifically different ways, and by many specifically different 10 constructions and arrangements of centrifugally operated devices. While, therefore, we have shown, and will now describe, various forms of centrifugally operated devices adapted for the accomplishment 15 of the objects and purposes of our invention we do not desire to be limited or restricted, to the specific details of construction or arrangement thereof, in the broadest scope of our invention as defined in the 20 claims.

In the drawing reference sign B, designates a portion of the coasting or drifting period indicating mechanism in connection with which our invention is employed. The 25 specific construction of indicating mechanism is not of material interest so far as our present invention is concerned, and therefore need not be specifically described or shown in detail herein.

30 A magnet C, is arranged to control the starting and stopping of the indicating mechanism. The circuit of this control magnet is arranged, in accordance with the principles of our invention, to be controlled, that is, to be opened or closed independently 35 in three different ways. In the first place, the circuit of this magnet is arranged to be opened automatically whenever current is supplied to the car or train propelling motor. This is accomplished through the 40 operation of a relay magnet D, arranged to be energized whenever current is supplied to the car or train propelling motor, and to remain energized as long as the current 45 supply to the car or train propelling motor continues. Whenever, however, the current to the car propelling motor is shut off this relay magnet becomes deenergized, thereby again completing the circuit of the recording 50 mechanism control magnet C, at the contact points controlled by the relay magnet. In the second place, other contacts arranged in the circuit of control magnet C, are arranged to be normally closed but to be separated whenever brake pressure is supplied 55 to the car or train brake mechanism. This is accomplished by means of a plunger operating in a cylinder E, which is in communication with the car or air brake system. The third point of control of the 60 circuit of control magnet C, is at the centrifugally operated mechanism, this mechanism being actuated by the travel of the car or train.

65 The current supplied to the relay magnet

D, may be furnished from any suitable or convenient source coincidently with the turning on or supply of current to the car propelling motor, through a circuit connection 12, thereto through the relay magnet coil D, and connection 13, to ground or other return 14. In this connection may be arranged, if desired, suitable removable or adjustable protecting fuses or similar devices F. When the relay magnet D, is energized it operates to rock a bell crank lever pivotally mounted as at 19, and having one arm 36, thereof arranged to form a movable armature for said relay magnet. To the other arm 35, of said bell crank lever is connected a rocking arm 32, carrying a contact point 30, arranged to coöperate with a contact point 28, arranged in the circuit of magnet C. Under normal conditions, with the circuit of relay magnet D, broken contacts 30 and 28, are closed upon each other. When the circuit of relay magnet D is completed the arm 32, is rocked and the contacts 30, 28, are separated. A second bell crank or movable lever 37, is connected to a pivoted lever 39, by means of a link 38, said lever 39, being arranged in the path of a rod 40, connected to a piston 26, operating in cylinder E. Carried by lever or bell crank 37, is an arm 33, carrying a contact 95 31, arranged to coöperate with a contact point 29, in the circuit of control magnet C. Under normal conditions contacts 31, 29, are closed upon each other. When, however, pressure medium is supplied to the air 100 brake system for application of the car or train brake mechanism the bell crank 37 is rocked and the contacts 31, 29, thereby separated. The circuit of control magnet C, may be supplied with current from any 105 suitable or convenient source, from the trolley, the car propelling motor, when operating as a generator, or otherwise, as may be convenient. We have shown the terminals of this circuit as being indicated 110 at a, and 51, respectively. From one terminal a, thereof the circuit is traced through connection 41, any suitable or convenient circuit protecting fuse or device 42, wire 43, magnet C, wire 44, contact 28, contact 115 30, arm 32, connection 34, arm 33, contact 31, contact 29, wire 45, to and through the centrifugal controlling mechanism to ground or other return connection 50 to the other terminal 51.

120 The centrifugal mechanism shown in Figs. 1 and 2, comprises a pair of rings 46, 49, insulated from each other and suitably mounted within a casing 47, but insulated therefrom and in concentric relation with 125 respect to a shaft 48, which may be a car axle or a propelling motor shaft or other revolving shaft having revolution during the travel of the car or train. Mounted upon but insulated from shaft 48, to revolve 130

therewith are arms 52, 53, carrying contact weights 54, at their free end. The arrangement is such that when shaft 48 is revolved the arms 52, 53, swing outwardly by centrifugal action thereby causing the contact weights 54, to engage the rings 46, 49, to bridge the space therebetween, thereby completing the circuit of the control magnet C, between said rings.

16 In Fig. 3 we have shown a modified arrangement wherein we dispense with one of the rings 46, 49, employing only one ring 60, concentric with shaft 48, and to which the circuit connection 45, of the control magnet C, is connected. In this case an arm 61 is pivotally connected directly to the shaft 48, and carries a contact 62, designed under centrifugal action to fly out and make contact with ring 60, thereby completing 20 circuit from said ring to ground through the axle 48, or to return through connection 50, to the terminal 51.

From the foregoing description it will be seen that we provide a simple arrangement 25 of centrifugally operated devices actuated by the travel or movement of the car or train for controlling separable contacts in the circuit of the magnet which controls the coasting or drifting period indicating mechanism, whereby, after the propelling power 30 for the car or train is shut off the indicating mechanism is put in operation and continues to operate only so long as the momentum or travel of the car or train while coasting or drifting is sufficient to generate 35 centrifugal action, and when the coasting or drifting travel of the train or car is completed the circuit of the control magnet of the indicating mechanism is open and the 40 action thereof arrested.

Having now set forth the object and nature of our invention and various forms of practical embodiment thereof, what we claim as new and useful and of our own invention, and desire to secure by Letters Patent of the United States, is,—

1. In an electrically operated indicating apparatus for vehicles, for indicating the coasting or drifting period of the vehicle, 50 electrically operated indicating mechanism, a circuit therefor, centrifugally operated means for closing the circuit of said indicating mechanism, said means being actuated by the vehicle when the vehicle is in motion.

2. In a coasting indicating apparatus for indicating the coasting or drifting travel of vehicles, an indicating mechanism, means for arresting the operation of said mechanism, and a centrifugally operated device actuated by the vehicle when the vehicle is in motion for controlling said arresting means.

3. In a coasting indicating apparatus for 65 indicating the coasting or drifting travel

of vehicles, an indicating mechanism, an electrical device for controlling the same, a circuit therefor and a centrifugally operated device actuated by the vehicle when the vehicle is in motion for closing said circuit, 70 an electrical device for opening said circuit when the vehicle propelling power is turned on.

4. In a coasting indicating apparatus for indicating the coasting or drifting travel of 75 vehicles, an indicating mechanism, an electrical device for controlling the same, a circuit therefor, a contact ring arranged in said circuit, a contact coöperating therewith, a centrifugally operated arm actuated 80 by the vehicle when the vehicle is in motion for supporting said last mentioned contact and actuating the same to close said circuit, an electrical device for opening said circuit when the vehicle propelling power is turned 85 on.

5. In a coasting indicating apparatus for indicating the coasting or drifting travel of vehicles, an indicating mechanism, an electrical device for controlling the same, a 90 circuit therefor, a contact ring arranged in said circuit, a shaft adapted to be rotated by the vehicle when the vehicle is in motion, and a contact centrifugally operated by said shaft and coöperating with said contact 95 ring to open and close said circuit and means to maintain said circuit open while the vehicle propelling power is turned on.

6. In a coasting indicating apparatus for indicating the coasting or drifting travel 100 of vehicles, an indicating mechanism, an electrical device for controlling the same, a circuit therefor, separable contacts arranged in said circuit, said contacts being normally closed upon each other, means for separating said contacts when current is supplied to the vehicle propelling motor, and centrifugally controlled contacts also arranged in said circuit, said centrifugally controlled contacts being actuated by the vehicle when 110 the vehicle is in motion.

7. In a coasting indicating apparatus for indicating the coasting or drifting travel of vehicles, an indicating mechanism, an electrical device for controlling the same, a circuit therefor, separable contacts arranged in said circuit and operating to normally contact with each other, means for separating said contacts coincidently with the application of brake pressure to brake the vehicle 120 and centrifugally controlled contacts also arranged in said circuit, said centrifugally controlled contacts being actuated by the vehicle when the vehicle is in motion.

8. In a coasting indicating apparatus for 125 indicating the coasting or drifting travel of vehicles, an indicating mechanism, an electrical device for controlling the same, a circuit therefor, brake pressure operated means for controlling said circuit, means con- 130

trolled by the current supply to the vehicle propelling motor for controlling said circuit, and centrifugally operated devices actuated by the vehicle when the vehicle is in motion for controlling said circuit.

In testimony whereof we have hereunto set our hands in the presence of the sub-

scribing witnesses, on this 23rd day of February A. D., 1911.

WALTER A. HALL.
